SILO CONSTRUCTION

Frank J. Van Cott and Leon J. Van Cott,
Unadilla, N. Y.

Application October 10, 1938, Serial No. 234,334

2 Claims. (Cl. 217—96)

An object of our invention is to provide a silo structure having improved features of construction which are simple and comparatively inexpensive to manufacture and also easily installed when the silo is assembled.

A further object is to provide a silo structure having an improved door lug provided with means to prevent it from rotating on the silo wall or from pulling loose from its position when strains are placed on the hoops and door rods of the silo.

A further object is to provide a door lug having a flange spaced from the inner edge of the door opening and imbedded in the silo wall in such manner that it is effective to prevent the door opening from decreasing in width as a result of exceptionally great strain applied to the hoops that extend from one door lug around the staves to the other door lug, such strain being a result of swelling of the staves.

Another object is to provide a base anchor for the silo structure which can be easily and inexpensively manufactured from strap iron, yet which is quite effective especially in conjunction with staves which are doweled together, to anchor the entire system of staves to the foundation for the silo structure.

Another object is to provide the base anchor in the form of a strap having its ends bolted to a plurality of staves and its central portion twisted to assume a position at substantially right angles to the silo wall, this portion being perforated whereby a tie rod extending up from the foundation may pass through the perforation of the strap and thereby the silo wall may be anchored to the foundation by a draw nut on the upper end of the tie rod and engaging against the central portion of the strap.

A further object is to provide the base anchor system of such character that the tie rods can be located substantially spaced from the finished wall of the silo, thus permitting initial positioning of the silo wall at a greater diameter than its finished diameter without interference by the tie rod, the rod however being effective after the base anchor strap has been installed to rigidly connect the silo with its foundation.

A further object is to provide a doweling system for a silo structure which utilizes spikes as the doweling means, there being guide bores in the staves of the silo wall which extend from the outer surface of the staves to their side edges, the spikes being passed through the guide bores and then driven into the edges of the adjacent staves whereby to rigidly hold the staves assem-

bled against longitudinal movement relative to each other.

Still a further object is to provide means to prevent the spikes from passing to the inner surface of the silo wall which consists in the use of side pointed nails or nails having off-center points, the points being located (when the spikes are driven into position) so that they will cause the driven portions of the nails to curve in their path of travel through the adjacent staves with the curvature being away from the inner surfaces of the staves.

Another object is to provide the guide bores on a slight incline relative to the horizontal so that any water getting into them will drain outwardly to the outer surface of the silo wall.

Still another object is to provide in connection with a silo structure a tank lug for the hoop rods thereof which can be inexpensively manufactured but has an extension means to prevent bending of the hoop rods adjacent the ends of the tank lugs without the necessity of making the bores for the hoop rods in the body of the tank lugs excessively long.

With these and other objects in view, our invention consists in the construction, arrangement and combination of the various parts of our silo structure, whereby the objects contemplated, and others as well, are attained, as hereinafter more fully set forth, pointed out in our claims and illustrated in the accompanying drawings, in which:

Figure 1 is a perspective view of a silo structure embodying our invention;

Figure 2 is an enlarged front elevation of one of the door lugs of our silo structure showing its coaction with adjacent parts of the structure.

Figure 3 is a sectional view on the line 3—3 of Figure 2.

Figure 4 is a sectional view on the line 4—4 of Figure 2.

Figure 5 is an enlarged sectional view on the line 5—5 of Figure 1 showing a base anchor of our silo structure.

Figure 6 is an enlarged front elevation of one of the tank lugs of our silo structure.

Figure 7 is a sectional view on the line 7—7 of Figure 6.

Figure 8 is an end elevation of the right hand end of Figure 6.

Figure 9 is an enlarged front elevation of two adjacent staves of our silo structure illustrating the doweling system which we use; and

Figure 10 is an enlarged sectional view on the line 10—10 of Figure 9.

On the accompanying drawings, we have used the reference character S to indicate generally a silo and F the foundation therefor. The silo S is composed of a plurality of vertically arranged staves 10 which form a cylindrical wall and terminate in door jamb members 12 between which doors 13 are mounted. The staves 10 have tongue and groove joints at their side edges as shown in Figures 3 and 5 and are doweled together by spikes 14 as will hereinafter be more fully described.

Extending around the silo S are hoop rods 15 and a door rod 16. These are connected together by tank lugs T and door lugs D. The door lugs D are castings or the like having short perforated bosses 17 for receiving the ends of hoop rods 15 and elongated bosses 18 for receiving the ends of the door rods 16. The tank lugs T have elongated bosses 19 and 20 for receiving the ends of the hoop rods 15. Draw nuts 21 and 22 on the door rods and hoop rods respectively engage the ends of the bosses 18, 17, 19 and 20 to draw the hoop assembly tight around the staves of the silo. The door lugs D are secured to the door jamb members 12 by bolts 23 and to the adjacent staves 10 by short nails 24.

Heretofore door lugs of the general character thus far described have been used but when there is sufficient swelling of the staves 10 to entirely take up the space within the silo hoops, the exceptionally great strain applied to the hoops that extend from one door lug D around the staves to the other door lug D, tends to draw on the bolts 23 and the nails 24 and move the door jamb elements 12 relative to the door lugs D in a direction toward each other, thus decreasing the distance between the door jambs. This so tightens the door 13 that it is extremely difficult to loosen it when desired. This excessive pull also tends to break the door lugs D.

Our present improvement resides in the formation of a flange 25, see Figures 2, 3 and 4, on the back of the door lug D. This flange is vertically arranged and adapted to be imbedded into the surface of the silo wall. Preferably it is countersunk in the outer edge of the door jamb member 12, which edge is notched at 26' for this purpose. The flange 25 being mounted in this position is away from the door opening so as to make a smooth unobstructed edge for the door 13 as shown in Figure 3 so that the door will fit tightly throughout its entire height. Also the flange is removed from any position of contact with the juices of the ensilage. By being imbedded in the wood of the wall, the flange reduces the tendency of the front lug to twist to a minimum and the flange serves as reinforcing means against breakage of the lug due to strains thereon. Imbedding of the flange in the silo wall also increases the amount of surface against the wood of the wall to counteract the pull on the hoops.

Considering the operation of the flange 25, it will be obvious that any swelling of the staves 10 is counteracted by the two staves adjacent the door jamb members 12 pressing their edges against the outer faces of the flanges. Thus the flanges serve as a much more effective means to prevent movement of the door jamb members 12 toward each other than the mere use of the bolts 23 and the nails 24 as heretofore used. Since the flange 25 prevents twisting of the lug, the trouble heretofore experienced of the hoops bending short at the ends of the lugs when tightening them, has been eliminated and the conse-

quent tendency of the door lug to break has likewise been eliminated.

In connection with the mounting of silo structures on their foundations, trouble has been experienced heretofore in providing an economical yet effective base anchor system. In our construction the staves 10 are doweled together by the spikes 14 and this prevents longitudinal movement of the staves relative to each other. Therefore in order to effectively anchor the entire silo wall on its foundation F, it is only necessary to connect with several staves of the silo wall at horizontally spaced points.

Our base anchor system includes straps 26 and tie rods 27. Each strap 26 has its ends against the silo wall and connected with a plurality of the staves 10 thereof by bolts 28. The central portion of the strap 26 is indicated at 29. This portion is twisted so that it lies in a plane at substantially right angles to the surface of the silo wall and is perforated as indicated at 30. It receives a threaded upper end of the tie rod 27 and a draw nut 31 is threaded on the rod. A washer 32 interposed between the nut and the central portion 29 of the strap serves as a reinforcing means for the perforated central portion when the nut is tightened. The lower end of each tie rod is imbedded in the foundation F as shown in section at the right hand side of Figure 1.

It will be noted that the lower end of the tie rod is spaced further from the silo wall than the perforation 30 in the portion 29 of the strap 26. This is because when laying the foundation F, the tie rods 27 are imbedded therein and in order that they do not interfere with the erection of the silo wall, they are spaced as illustrated because the staves when being assembled are placed two to four inches outside the circle they are to eventually assume. Finally the hoops are put around them and the staves are tightened to their final position, whereupon the tie rods 27 may be bent inwardly to properly coat with the base anchor straps 26 in the positions they assume when bolted on the silo wall. The tie rods 27 have long threaded upper ends so that they can be imbedded in the foundation F when it is formed without the necessity of locating them in an exact position and can be readily bent after the silo wall is set up to proper position for coacting with the anchor straps 26 to draw the silo against its foundation and thereby anchor it in position.

For the dowels or spikes 14, we provide guide bores 33. The guide bores 33 extend from a point at the outer surface of the stave (the right hand surface in Figure 10) to the edge of the stave.

In Figure 10 the guide bore is shown in solid lines in the lower stave and the spike in this bore has been driven to its final position with the head 14a thereof enlarging the outer end of the guide bore 33 as at 34. During such driving of the spike, it forms its own opening 35 in the adjacent or upper stave. The spikes 14 are of special "side-pointed" type or the type having off-center points. The points are illustrated at 36 in Figure 10 and it will be noted that the offset of the point is toward the outer surface of the silo wall. This causes the bore 35 to have a curvature produced by the driving of the side-pointed nail into position. The off-center point of course is properly located by the silo assembler so that the curvature is outward and thus we eliminate the possibility of the spike following the grain and coming out on the inner surface

of the wall where it might split the stave and be exposed on the inner surface of the silo wall to the ensilage juices which would cause rusting of the nail. Also the possibility of roughening the inner surface of the silo wall is eliminated which would result in improper settling of the ensilage.

A further improved feature of our doweling system is the formation of the guide bores 33 so that they slope downwardly from their inner ends to the outer surface of the silo wall as shown in Figure 9. This prevents water from getting in and drains out any that does get into the bores and thus eliminates the possibility of water remaining in the bores and rotting the staves. The curvature which the spikes 14 assume when driven into position prevents any pulling apart or slippage between the edges of the silo staves 10. The curvature of the spike also greatly resists any pulling of the nail from position when compared with the ordinary center-pointed spike.

Our tank lug T has its elongated bosses 19 and 20 bored at an incline relative to each other as shown in Figure 7 to receive straight ends of the hoop rods 15. The intermediate portions of the rods of course are curved to fit the surface of the silo wall. In order to make the lug T economically a minimum of metal must be used in its construction. If the bosses 19 and 20 are made too short, however, there is a tendency for the lug to twist instead of having a straight 30 pull on the rods 15 when the nuts 22 are tightened.

To counteract this tendency without making the bosses 19 and 20 longer, we form an extension 37 on one end of the boss 19 and a similar extension 38 on one end of the boss 20. These extensions contact, as shown by the extension 38 in Figures 7 and 8, with a portion of the hoop rod where there is a tendency to bend the rod when the nut 22 is tightened. The extensions 37 and 38 are accordingly diagonally arranged in Figure 6 as the points indicated at 40 are the bending points of the rods upon tightening thereof. Thus, by the simple expedient of making extensions only at advantageous points, we secure the benefit of longer bosses 19 and 20 without the necessity of using as much metal as would be necessary to make them longer. Our construction results in a straighter 50 pull on the hoop rods with a reduction in the tendency of the tank lugs to twist and the rods

to bend and thus become difficult to properly tighten.

The constructional features herein described all contribute to making a silo structure which 5 is economical to manufacture and assemble, yet one which is efficient for the purposes of storing ensilage and which will last longer than the usual types due to the improved constructional features.

10 Some changes may be made in the construction and arrangement of our silo structure without departing from the real spirit and purpose of our invention. We therefore intend to cover by our appended claims such modified forms of 15 structure or use of mechanical equivalents as may be reasonably included within their scope.

What we claim as our invention and desire to secure by Letters Patent of the United States is:

1. In a silo structure, a wall circular in cross 20 section comprising a plurality of staves having substantially flat outer surfaces and edges adapted to engage one with another, each said stave having two sets of guide openings, one of said sets comprising a plurality of spaced apart openings extending from the outer surface in an oblique inwardly and upwardly direction through the edge at one side thereof, the other of said sets comprising a plurality of spaced apart openings alternating with the openings of said first set and extending in an oblique inwardly and upwardly direction through the edge at the other side thereof, and dowels in said openings extending respectively into the edges of adjacent staves on both sides of each said stave.

2. In a silo structure, a wall circular in cross 35 section comprising individual staves having substantially flat outer surfaces and edges adapted to engage one with another, a plurality of said staves each having two sets of guide openings, one of said sets comprising a plurality of spaced apart openings extending from the outer surface in an oblique inward direction upward through the edge at one side thereof, the other of said sets comprising a plurality of spaced apart openings extending in an oblique inward direction upward through the edge at the other side thereof, and dowels in said openings extending respectively directly into the edges of adjacent 40 staves on both sides of each of said plurality of staves.

FRANK J. VAN COTT.
